J. E. MEROOTT COMPANY, OF NEWARK, NEW JERSEY, A CORPORATION OF NEW
JERSEY.

PROCESS OF FORMING BAG-FRAMES.

1,049,302.

Specification of Letters Patent. Patented Dec. 31, 1912.

Application filed April 22, 1909. Serial No. 491,565.

To all whom it may concern:

Be it known that we, CHRISTIAN HIERING and ALBERT FULLER, citizens of the United States, residing in the city of Newark, county of Essex, and State of New Jersey, have invented a certain new and useful Process of Forming Bag-Frames, of which the following is a full, clear, and exact description, such as will enable others skilled 10 in the art to which it pertains to make, construct, and use the same.

The primary object of this invention is the production of angular bag frames for bags and purses, and especially for traveling 15 chatelaine and similar bags by a process which consists in first cutting a blank of the requisite form from sheet metal, said blank comprising a main body member and angular pivot members, then, by means of suitable punches and dies, angling the major portion, or the entirety of the main body member, and finally angling the hinge members to form the completed member with sharp corners, or first angling the major 20 portion of the main body member, thereafter angling the corner of the blank and finally angling the hinge members to form the completed member with sharp corners, or first angling the major portion of the main body member, thereafter angling the corner of the blank and finally angling the hinge members to form the completed member with sharp corners, or first angling the major portion of the main body, corner and one hinge member, and thereafter angling the remaining portion 25 of the main body member, other corner and hinge member to form the completed member with sharp corners.

Hitherto, in the construction of bag frames of the type to which our invention relates, it has been customary to form at first a blank as illustrated in full lines in Figure 6, and thereafter by suitable drawing 30 dies, simultaneously draw up the metal around the three edges of the blank, and thereafter, cutting out the blank on the dotted lines indicated in said figure. This process is objectionable for the reason that 35 while it lends itself admirably to soft metal, it is not at all adapted when it is desired to use what is known in the trade as quarter, half or hard metal, and for the further reason that the metal indicated by the dotted 40 lines is waste material.

With our improved process, it is not necessary to cut a blank of the outline indicated in Fig. 6 having a solid center, but one which has the dimensions and outlines indi-

cated in Figs. 1 and 7, and other of the several views illustrated, and which comprises a main body portion and the two hinge members. Furthermore, distinct and important advantages are gained with this form of blank and the steps necessary to 55 form it with angular corners. We are enabled to discard the heretofore undesirable soft material, and substitute hard material, thereby producing a frame member possessing more rigidity and stability than those 60 heretofore made and simultaneously reducing the amount of waste, common in the manufacture of bag frames of this type, to a minimum.

In the accompanying drawings forming a 70 part of this specification; Fig. 1 represents the sheet metal blank which subsequently forms the angled bag frame member with sharp corners. Fig. 2 represents the major portion of the main body member of said 75 blank angled. Fig. 3 represents the result of the next operation of angling the one corner and the hinge member. Fig. 4 represents the result of the subsequent operation of angling the other corner and hinge member. Fig. 5 represents a sectional view of 80 two of the bag frame members secured together. Fig. 6 represents a plan view of the blank, hitherto used indicating in dotted lines the waste of said blank. Fig. 7 represents another form of a sheet metal blank, which subsequently forms the angled bag 85 frame members with sharp corners. Fig. 8 represents the major portion of the main body member of said blank angled. Fig. 9 represents the result of the next operation of 90 angling one corner of said blank. Fig. 10 represents a part of the main body member of said blank angled. Fig. 11 represents the result of the next operation of angling 95 one corner and the hinge member of said blank. Fig. 12 represents the result of the subsequent operation of angling the other corner and hinge member. Fig. 13 represents a sectional view of two bag frame 100 members secured together. Fig. 14 is a sectional view taken on line $x-x$ of Fig. 12. Fig. 15 represents a sectional view of another form of three bag frame members secured together. Fig. 16 represents an end 105 view of the same. Fig. 17 represents an angled inlay for bag frames; and Fig. 18 a section thereof.

Similar letters of reference refer to like parts throughout the specification and drawings.

In describing the process forming a part 5 of our invention, we will simultaneously describe the product of the same, so that those skilled in the art to which it pertains, may gain a full knowledge of the process as well as the product.

10 In Figs. 1 and 7, we have shown the sheet metal blanks *a* and *a'* as they are punched out. Since the blanks form three sides of a hollow rectangle, the resulting waste is reduced to a minimum, and may be further 15 reduced by alternating the blanks as illustrated in Fig. 1. The blanks *a* comprise a main body portion *b* and the two hinge portions *c* at right angles thereto. To complete the frame members with sharp corners, 20 the outer edge portion of the blank is bent up or angled along the dotted lines of Fig. 1, so that a cross section is, as shown in Figs. 5, 13 and 14, where *A* represents an completed frame member made from the blank *a* and *A'* 25 one made from the blank *a'* of Fig. 7. It will be seen that the main body portion *b'* of the blank *a'* is made wider than the hinge portions *c*, thereby producing in the completed frame member *A'* a flange extending 30 beyond the plane of the edges of the angled hinge members as clearly shown in Figs. 13 and 14. As shown, these sheet metal blanks *a* are blanked out in such a way as to nearly resemble the finished frame member, which 35 as previously stated, comprises the main body member *b*, and the two angular hinge members *c*, as distinguished from the blank illustrated in full lines in Fig. 6, in which it was necessary to cut out a blank as shown, 40 and then by means of a simple drawing die, angle or draw up at one operation, the main body member and the rectangular hinge members, and thereafter cutting out the blank on the dotted lines indicated in said 45 figure, said portion indicated by the dotted lines representing the waste material. The process just described in connection with the blank illustrated in Fig. 6 of the drawings, did lend itself admirably to the here- 50 tofore soft material used, but is absolutely impractical when applied to what is known in the trade as hard material, for the reason that in the subsequent operation of drawing up or angling the sides of said blank, the 55 metal at the angled portion of the blank would break, owing to the hardness of the same. We have also found it to be impractical to take a blank as indicated in Figs. 1 and 7 of the drawings of either soft or hard 60 material, and subject it to the operation of simultaneously angling or drawing up by means of a drawing die, the main body member and hinge members of said blank, for the reason that the metal of the main 65 body member and of the hinge members

constituting the inner edge of the blank, would be drawn out of shape, thereby producing a very much distorted frame member having a shape similar to the one indicated in dotted lines in Fig. 12.

In order to overcome the aforesaid difficulties, we have found it advantageous to construct a blank as indicated in Figs. 1 and 7, and then by means of suitable and simple punches and dies, angling the major 75 portion of or the entire portion of the main body member, as indicated in Figs. 2, 8 and 10, and finally angling the hinge members and corners of said blank to form the completed member with sharp corners, as illustrated 80 in Figs. 4 and 12.

Sometimes, we find it convenient to first angle the major portion of the main body member, as indicated in Fig. 8, thereafter angling the corner of the blank as indicated 85 in Fig. 9, and finally angling the hinge members to form the completed member with sharp corners, as indicated in Fig. 12.

By the process described in connection with the blank in Fig. 7, we are enabled to 90 produce a bag frame member, the main body portion *b'* of which has formed thereon an angle or flange of greater depth than those of the hinge members *c* as illustrated in Figs. 13, 14, 15 and 16, in which the 95 angled portion extends over and overlaps the angled portion of the other frame member, (see Fig. 13) thereby producing when assembled a bag frame of extremely neat appearance and novel construction.

100 A novel product of this process is further illustrated in Figs. 15 and 16, in which three members constitute the completed bag frame, two of which, namely, the outer ones *A*², *A'*² are provided at the main body portion with an angle or flange of greater 105 depth than those of the hinge members, the space between the hinge members permitting the interposition of an auxiliary member *A*³; the wider angled portions of the 110 main frame members *A*² cover the top of the auxiliary frame and the hinge members of said auxiliary frame filling in the space 115 between the two outer frame members, which, when so assembled, produce an even 120 surface extending entirely around the frame sections.

Another novel product of this process is 125 illustrated in Figs. 17 and 18, which shows the form of inlay used in connection with the above described bag frame members. It will be seen that the inlay *B* is angled in the same manner as the frame member *A* shown in Fig. 4, except that the angled portion is only deep enough to accommodate the thickness of the leather which is to be inserted between the inlay and the bag frame member, and thereafter held in place by rivets through the inlay and frame member in the usual manner. The manner of 130

angling the inlay is the same as for the frame member A; that is, the body member of the inlay and the angle members thereof are separately angled to produce the completed inlay.

By the process described, and the use of the very simple punches and dies employed, we are enabled without inconvenience to use metal, the standard gage of which sometimes materially varies without affecting the tools and the product, inasmuch as this process of independently angling the sides of the blank, as distinguished from angling or drawing up the sides of the blank simultaneously as heretofore done, enables us to dispense with an accurately fitting punch and die, the dimensions of which have to be kept up to a size to accommodate material of a given thickness and substitute therefor a punch and die of very simple construction, which can be set up with relation to each other to accommodate the material of varying thicknesses.

We claim:

1. The process of forming sheet metal bag frame members, which consists in cutting a flat U-shaped blank from sheet metal, said blank comprising a main body member and angular hinge members extending from the ends thereof, then progressively bending the blank transversely and longitudinally at a sharp right angle while preserving the inner contour of the inner edge of the blank to form the completed bag member with a continuous jointless sharp cornered flange extending along the outer edges of the main body member and the hinge members.

2. The process of forming sheet metal bag frame members, which consists in cutting a flat U-shaped blank from sheet metal, said blank comprising a main body member and angular hinge members, forming a continuous jointless sharp cornered flange extending along the outer edges of the main body member and the hinge members while preserving the contour of the inner edge of the blank by first bending the edge of the main body member longitudinally at a sharp right angle and thereafter bending the hinge members transversely at a sharp right angle.

3. The process of forming sheet metal bag frame members which consists in cutting a flat U-shaped blank from sheet metal, said

blank comprising a main body member and angular hinge members, forming a continuous jointless sharp cornered flange extending along the outer edges of the main body member and the hinge members while preserving the contour of the inner edge of the blank by first bending the main body member longitudinally at a sharp angle, then bending the corner longitudinally and transversely at a sharp angle, and thereafter bending the hinge members transversely at a sharp angle.

4. The process of forming sheet metal bag frame members, which consists in cutting a flat U-shaped blank comprising a main body member and angular hinge members, then forming a continuous jointless sharp cornered flange extending along the outer edges of the main body member and the hinge members while preserving the inner contour of the inner edge of the blank by first bending the major portion of the main body member longitudinally at a sharp right angle, thereafter bending the corners at a sharp right angle, and finally bending the hinge members transversely at a sharp right angle to form the completed member.

5. The process of forming sheet metal bag frame members, which consists in cutting a flat U-shaped blank comprising a main body member and angular hinge members, forming a continuous jointless sharp cornered flange extending along the outer edges of the main body member and the hinge members while preserving the contour of the inner edge of the blank by first bending the major portion of the main body member longitudinally at a sharp right angle, and the corner and one hinge member transversely at a sharp right angle, and thereafter bending the remaining portion of the body member, and the other hinge member longitudinally and transversely at a sharp right angle to form the completed bag member.

This specification signed and witnessed this 21st day of April, 1909.

CHRISTIAN HIERING.
ALBERT FULLER.
